SIGN LIGHT LENS

William H. Dorman, Corning, N. Y., assignor to Corning
Glass Works, Corning, N. Y., a corporation of New
York

Application March 12, 1957, Serial No. 45,222

Term of patent 14 years

(Cl. D48—16)

Fig. 1

Fig. 2

Fig. 3

Fig. 1 is a front elevational view of a sign light lens embodying my new design.

Fig. 2 is a sectional view taken on line 2—2 of Fig. 1.

Fig. 3 is a side elevational view thereof.

Although the lens shown is composed of transparent glass, such prisms thereof as are visible through the glass are blurred to such an extent as to make their showing impracticable.

I claim:

The ornamental design for a sign light lens, as shown.
